ROOFING AND SIDING ELEMENT AND
METHOD OF PRODUCING CONTRASTING
EFFECTS THEREONNorman P. Harshberger, Pasadena, Calif., as-
signor to Bakelite Building Products Co. Inc.,
New York, N. Y., a corporation of Delaware

Application April 11, 1930, Serial No. 443,602

3 Claims. (Cl. 91—67.9)

This invention relates to improvements in roofing and siding elements and method of producing contrasting effects thereon.

In the composition roofing art, it is frequently desirable to produce designs or lines of demarcation on roofing strips to simulate a plurality of individual shingles. Heretofore, said designs have been formed mainly by coloring certain portions of the surface differently from other portions thereof. Lines of demarcation have also been produced by depressing certain portions of the surface to create shadow effects. However, when a material is depressed which is surfaced with mineral matter of the usual coarseness, the said mineral matter is likely to rupture the felt base and to weaken the material.

It is one of the objects of this invention to provide improved roofing and siding material and method of producing contrasting effects thereon in which lines of demarcation are formed by depressing portions of the surface, but in which no weakening of the felt base results from creating said depressed portions.

A more specific object of this invention is to provide an article and method of the class described in which the material is surfaced with relatively fine mineral particles in the areas which are to be depressed, so that the fabric base will not be cut into as is now the case where pressure is exerted upon the coarse mineral material.

A further object of this invention is to provide roofing and siding material and method of producing the contrasting effects thereon which is simple, effective and well adapted for the purpose described.

With the above and other objects in view, the invention consists of the improved roofing and siding material and method of producing contrasting effects thereon, and all its parts and combinations as set forth in the claims, and all equivalents thereof.

In the accompanying drawing illustrating one embodiment of the preferred form of the invention, in which the same reference numerals designate the same parts in all of the views;

Fig. 1 is a plan view of a strip of roofing material showing the features of the invention embodied therein; and

Fig. 2 is a sectional view taken on line 2—2 of Fig. 1.

Referring to the drawing, the usual type of composition roofing material is employed, the said material consisting of a fabric base 5 which is saturated and coated with bituminous material

6. In the strip of material shown, it is desired to produce transverse lines of demarcation, so that the strip will simulate a plurality of individual shingles. Accordingly, the major portion of the face of the strip is covered with a layer 80 of crushed slate or mineral material 7 of the usual coarseness. Narrow areas 8 are protected during this step of the method. Subsequently the protecting means is removed and the areas 8 are then covered with comparatively fine particles of mineral material 9. Next, pressure is exerted on the strip by any suitable means to form recessed portions 10, in which the bituminous material is depressed, and in which the fine particles of mineral material are pressed 65 down with said bituminous material adjacent the felt base. Due to the fact that fine particles of mineral matter are employed to cover the portions of the surface which are to be depressed, these fine particles will not dig into 70 the fabric base to weaken the same when pressure is exerted to create the recesses 10. If a coarse mineral matter such as is now employed in standard practice, were used to cover the entire face, the said coarse particles would dig 75 into the felt base to weaken the latter along 80 the depressed lines.

In the resulting product, the lines of demarcation will stand out prominently in view of the fact that a shadow effect will be created, and in view of the fact that the fine mineral material therein will give a slightly different effect from the mineral material of the usual coarseness which is used on the other portions of the strip.

Substantially the same result can be produced by using a comparatively fine stone, preferably in a double layer, over the entire face of the web, and by depressing portions of the surface along desired lines or in desired areas as above described. With this method, there will be no danger of cutting into the fabric base, and the shadow effects will be produced as effectively. There will not, however, be the slight difference of appearance between the mineral particles in the depressed areas and the mineral particles on the rest of the strip as in the preferred form 100 where mineral material of two degrees of coarseness is employed.

From the foregoing description, it may be seen that a very desirable method has been provided in which contrasting effects are produced in a very novel manner by depressing portions of the surface, and in which no weakening of the fabric base results from creating said depressed portions.

What I claim is:

1. As an article of manufacture, roofing and siding material comprising a fibrous base presenting a granulated-particle surface secured to said base by a bituminous adhesive layer, said surface presenting depressed areas, said depressions extending into the adhesive layer substantially close to but not into the base, and said depressed layer presenting granulated material of greater fineness than that on the undepressed portions and being substantially on a level with the depressed bituminous surface, the depth of the depressions being limited by the size of the finer particles to avoid their extending through the adhesive layer and to prevent weakening of the fibrous base.
- 10 2. A method of producing roofing and siding elements with accentuated contrasting effects which comprises applying large and small sized

20

granular surfacing particles to different areas of the surface of a saturated and bituminous coated fabric base, and depressing the areas surfaced with the small sized particles until the particles are close to the fabric base to accentuate the contrast, the depth of the depression being limited by the size of the particles to avoid puncturing the fabric.

80

3. A composition roofing and siding element comprising a saturated fibrous base having a bituminous coating material surfaced with large and small sized granular surfacing particles applied to different areas, the parts of the surface covered with the small sized particles being depressed close to the fabric and the depth of the depression limited by the size of the particles to avoid puncturing the fabric.
